UNITED STATES PATENT OFFICE.

WILLIAM BLACKMORE, OF SHARON, PENNSYLVANIA, ASSIGNOR OF ONE-THIRD TO
ELMER BELL, OF SHARON, PENNSYLVANIA, AND ONE-THIRD TO WILLIAM C.
BLACKMORE, OF CLEVELAND, OHIO.

SNUBBER ATTACHMENT FOR VEHICLE SPRINGS.

Application filed July 7, 1926. Serial No. 120,956.

The present invention relates to a snubber attachment for vehicle springs, the snubber attachment of the present invention being of the type in which pressure is applied to 5 superposed leaves of the spring to resist relative longitudinal movement of the leaves and prevent excessive flexure of the spring, either downwardly due to the impact on the supporting wheels or upwardly due to the 10 rebound.

I am aware that the idea of checking the flexure of a leaf spring by applying clamping pressure to the leaves thereof to increase the friction between them is not broadly 15 new but in so far as I am aware no snubbing device of this character has heretofore come into general use.

The present invention has for its object to provide a device of this character capable 20 of withstanding the hard usage to which it is subjected in service and of such simple construction that it may be manufactured at a low cost.

A further object of the invention is to 25 provide a clip for supporting the spring clamping element which is formed of resilient metal, permitting it to yield and prevent application of excessive pressure to the leaves of the spring and also preventing 30 damage to the clip and to the clamping devices carried thereby.

Further objects of the invention are to 35 simplify and otherwise improve the connections between the vehicle body or axle and the spring clamping means and to provide a more durable, more reliable and more effective spring clamping device.

With the above and other objects in view the invention may be said to comprise the 40 device as illustrated in the accompanying drawings hereinafter described and particularly set forth in the appended claims, together with such variations and modifications thereof as will be apparent to one 45 skilled in the art to which the invention appertains.

Reference should be had to the accompanying drawings forming a part of this specification, in which:

50 Fig. 1 is a side elevation showing the snubber attachment applied to a semi-elliptic leaf spring of the type employed in automobiles of various makes;

Fig. 2 is a fragmentary side elevation

showing the spring clamped device in side 55 elevation on a larger scale than in Fig. 1;

Fig. 3 is a section taken on line 3—3 of Fig. 2;

Fig. 4 is a section taken on line 4—4 of Fig. 3;

Fig. 5 is a section taken on line 5—5 of Fig. 3;

Fig. 6 is a rear elevation showing the invention applied to the rear spring of an automobile of a well-known type;

Fig. 7 is a front elevation showing a modified form of leaf clamping device applied to a front spring of an automobile of a well-known type; and

Fig. 8 is a section taken on line 8—8 of Fig. 7.

In Fig. 1 of the drawing, there is shown a side member 1 of an automobile frame, an axle 2, a leaf spring 3, connected at its center to the axle by means of a clamp 4, at its 75 front end to the frame member 1 by means of a pivot pin 5 and at its rear end to the frame member 1 by means of a shackle 6.

The device of the present invention is adapted to be applied to the leaf spring and 80 to exert a clamping pressure upon a plurality of superposed leaves thereof to limit the flexure of the spring. The spring engaging clamping members are carried by a substantially U-shaped clip 7 which is formed of re- 85

silient metal, such as spring steel, and is adapted to be slipped over the spring 3 between the center and one of the ends thereof. The clip 7 has an upper arm 8 which overlies the top leaf of the spring and which is 90 provided with a set screw 9, adapted to be screwed down into engagement with said top leaf and held with a lock nut. The clip 7 is also provided with a lower arm 10 which extends beneath the spring and is provided with an upwardly projecting flange 11 at its 95 outer end. Within the flange 11, there is mounted, upon the lower arm 10, a bearing block 12 which is provided with a concave recess 13 on its upper side. A cam 14 is interposed between the bearing block 12 and the underside of the spring. The cam 14, which is substantially triangular in shape, has a rounded apex 15 which engages in the concave recess of the bearing block 12, the cam being supported on the bearing block with its base uppermost beneath the spring 100

3, the base of the cam being provided with a 105

suitable wear plate 16 which engages with the lower leaf of the spring. Sufficient space is provided between the upper edge of the flange 11 and the outer end of the arm 8 of the clip to permit the clip to be slipped into place on the spring and when the clip is positioned on the spring, the set screw 9 may be turned to clamp the spring with the desired pressure against the flat face of the cam 14. The flange 11 has a slot 17 extending downwardly from the upper end thereof and the cam 14 has an integral arm 18 which extends laterally through the slot and is bent at right angles to extend upwardly along the side of the spring 3. The upper end of the arm 18 is slidably supported in an eye bolt 19, attached to the under side of the frame member 1.

When the attachment is put in place on the spring, the set screw 9 is tightened sufficiently to hold the spring snugly against the flat upper face of the cam 14. When the ends of the spring 3 are flexed downwardly, due to the impact of the wheels of the vehicle in passing over irregularities in the road surface, the frame member 1 will move downwardly toward the axle 2, rocking the arm 18 and turning the cam 14 on the rocker bearing 12, causing the cam to exert an increased pressure upon the superposed leaves of the spring with the result that the frictional resistance to relative longitudinal movement between the leaves of the spring is greatly increased, stiffening the spring and limiting the flexure. When on the rebound the frame member 1 moves upwardly above its normal position, the arm 18 and cam 14 are rocked in the opposite direction again causing the cam to exert a clamping pressure upon the leaves of the spring to limit the upward flexure of the spring. Since the clip 7 is formed of resilient metal, the arms 8 and 10 thereof will be sprung slightly apart when excessive pressure is exerted upon the cam 14 and this yielding of the clip prevents damage to the spring and to the clamping devices since it limits the pressure applied by the cam to the spring and permits the arm 18 to have the necessary range of movement to accommodate the movements of the frame member 1 when the wheels of the vehicle are subjected to excessive impacts.

In Fig. 6 of the drawing, the invention is shown applied to a different type of spring, the spring in this case being a well-known type of rear spring. In this case, the spring 20 is interposed between a rear axle 21 and a vehicle frame member 22, the frame member being supported upon the central portion of the spring and the opposite ends of the spring being connected to the axle by suitable shackles 23.

The clip and the clamping devices carried thereby are identical with the clip and

clamping devices above described and the attachment shown in Fig. 6 differs from that above described only in that the actuating arm extends from the clip to the axle instead of from the clip to the supporting frame and in that a slightly different connection is provided between the axle and actuating arm. As shown in Fig. 6, the actuating arm 18^a extends inwardly and downwardly from each of the clips 7 and each of the two arms 18^a is provided with an elongated slot 24 adjacent its inner end, which receives the clamping bolt 25 of a sectional collar 26 secured upon the axle 21.

Upward or downward movement of the frame member 22 from its normal position will cause the arms 18^a and the cams carried thereby to be rocked about their pivots to apply clamping pressure to the leaves of the spring and limit the flexure thereof.

In Fig. 1 of the drawing, the cam actuating arm is shown connected to the vehicle frame member whereas in Fig. 6, the cam actuating arm is shown connected to the axle of the vehicle. It will be obvious, therefore, that it is immaterial, so far as the present invention is concerned, whether the cam actuating arm is attached to the frame member or to the axle, the same result being accomplished when the actuating arm is connected to either of the relatively movable parts of the vehicle between which the spring is interposed.

In Figs. 7 and 8 of the drawing, there is illustrated a modified form of the invention in which a uniform clamping pressure is maintained upon the leaves of the spring to increase the resistance to bending movement and to thereby stiffen the spring. In this form of the invention, a substantially U-shaped clip 27 of resilient metal, such as spring steel, is provided and this clip has an upper arm 28 which overlies the top leaf of the spring and carries a grease cup 29 for lubricating the spring and a lower arm 30, which overlies the spring and carries a set screw 31 by means of which clamping pressure may be applied to the spring. The set screw 31 may be tightened upon the spring until the spring is held with the desired pressure and the set screw may be held in adjusted position by means of a lock nut 32 which is carried by the set screw below the arm 30 and is adapted to be screwed into engagement with the arm 30 to hold the set screw against turning movement. The attachment shown in Figs. 7 and 8 is designed particularly for a small automobile of a well-known make and is shown applied to the front spring 33 of such an automobile.

Having thus described my invention, what I claim is:

1. The combination with a spring formed of superposed leaves which have a relative

endwise movement upon flexure of the spring, of a substantially U-shaped clip formed of resilient metal and having a base portion and a pair of spaced arms extending laterally from the base portion, said clip being adapted to be placed on the spring with the base extending across one side of the spring and the arms extending across the leaves at the top and bottom thereof, and means mounted on one of the arms for applying a clamping pressure to the superposed leaves of the spring.

2. The combination with a spring formed of superposed leaves which have a relative endwise movement upon flexure of the spring, of a substantially U-shaped clip formed of resilient metal and having a base portion and a pair of spaced arms extending laterally from the base portion, said clip being adapted to be placed on the spring with the base extending across one side of the spring and the arms extending across the leaves at the top and bottom thereof, and a set screw carried by one of the arms for applying a clamping pressure to the superposed leaves of the spring.

3. The combination with a vehicle having frame and axle members and an interposed leaf spring, of a snubber attachment comprising a clip of resilient metal having spaced arms adapted to straddle a plurality of leaves of the spring, a movable pressure applying device interposed between one of said arms and the adjacent leaf of the spring, and means connecting said device with one of said members for actuating said pressure applying device upon a relative movement of said members.

4. The combination with a vehicle having frame and axle members and an interposed leaf spring, of a snubber attachment comprising a clip of resilient metal having spaced arms adapted to straddle a plurality of leaves of the spring, a movable pressure applying device interposed between one of said arms and the adjacent leaf of the spring, and means connecting said device with one of said members for actuating said device to apply pressure to superposed leaves of the spring upon relative movement of said members in either direction from their normal position.

5. The combination with a vehicle having frame and axle members and an interposed leaf spring, of a snubber attachment comprising a clip having spaced upper and lower arms adapted to receive a plurality of leaves of the spring between them, a cam mounted on one of the arms and interposed between said arm and the adjacent leaf of

the spring, and an arm fixed to the cam and slidably connected to one of said members whereby said cam is actuated to apply clamping pressure to the superposed leaves of the spring upon relative movement of said members.

6. The combination with a vehicle having frame and axle members and an interposed leaf spring, of a snubber attachment comprising a clip having spaced upper and lower arms adapted to receive a plurality of leaves of the spring between them, a cam mounted on one of the arms and interposed between said arm and the adjacent leaf of the spring, a set screw carried by the other arm for clamping the superposed leaves of the spring against said cam, and an arm fixed to the cam and slidably connected to one of said members whereby said cam is actuated to apply clamping pressure to the superposed leaves of the spring upon relative movement of said members.

7. The combination with a vehicle having frame and axle members and an interposed leaf spring, of a snubber attachment comprising a clip having spaced upper and lower arms adapted to receive a plurality of leaves of the spring between them, a cam mounted on one of the arms and interposed between said arm and the adjacent leaf of the spring, a bearing block carried by one of the arms on the inner side thereof and having a concave bearing recess, a substantially triangular cam having a rounded apex fitting in said recess and a base bearing against an outer leaf of the spring, and an arm fixed to said cam and connected to one of said members.

8. The combination with a vehicle having frame and axle members and an interposed leaf spring, of a snubber attachment comprising a clip having spaced upper and lower arms adapted to receive a plurality of leaves of the spring between them, a cam mounted on one of the arms and interposed between said arm and the adjacent leaf of the spring, a bearing block carried by one of the arms on the inner side thereof and having a concave bearing recess, a substantially triangular cam having a rounded apex fitting in said recess and a base bearing against an outer leaf of the spring, an arm fixed to said cam and connected to one of said members, and a set screw carried by the other arm of the clip for clamping the superposed leaves of the spring against said cam.

In testimony whereof, I hereunto affix my signature.

WILLIAM BLACKMORE.
